UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

STRAIGHTAWAY BLINDSTITCH SEWING-MACHINES.

1,291,503.

Specification of Letters Patent.

Patented Jan. 14, 1919.

Application filed January 20, 1915. Serial No. 3,403.

To all whom it may concern:

Be it known that I, THOMAS J. HAYES, a citizen of the United States, and resident of Roslindale, county of Suffolk, State of Massachusetts, have invented an Improvement in Straightaway Blindstitch Sewing-Machines, of which the following description, in connection with the accompanying drawing, is a specification, like characters on 10 the drawing representing like parts.

This invention relates to improvements in blind stitch sewing machines for felling, padding and the like in which a series of stitches are formed by a curved needle oscillating in a fixed plane and inclined to the work supporting surface of the work support and lying parallel or substantially parallel to the line of stitching.

In blind stitching machines heretofore made and particularly the class of blind stitching machines which are adapted for felling a superimposed layer of material upon a base layer of material, the curved oscillating needle is vibrated in different planes, mechanism being provided whereby upon one series of oscillations the needle will penetrate the base layer and upon the alternating series of oscillations the needle will penetrate the superimposed layer, the 30 threads laid in these layers being concatenated and the concatenated loops drawn into one or the other of said layers. In some forms of blind stitching machines the needle penetrates the superimposed layer at or adjacent to the edge thereof and emerges from the upper face of said layer at a distance back from the edge so that the threads concatenating the loops laid by the needle are drawn over the edge of the goods making a 40 seam which is difficult if not impossible to conceal.

In my prior application No. 784,687, filed Aug. 14, 1913 Patent #1,230,159, June 19, 1917, a machine is disclosed in which a 45 curved needle is oscillated alternately in parallel planes inclined to the work supporting surface of the work support, the needle being shogged, first to engage the base layer which is presented to the needle by suitable bender mechanism, and second the superimposed layer. In the latter case the needle will, by reason of its oscillation in a plane inclined to the surface of the

work support enter well beneath the superimposed layer before its point penetrates 55 said layer and will emerge from the superimposed layer at or beneath the edge thereof. The blind stitch made by this machine is entirely concealed beneath the edge of the superimposed layer.

The present invention contemplates the production of a machine in which a curved needle oscillating in a plane inclined to the work supporting surface of the work support may be caused to penetrate both the 65 base and superimposed layer upon each stroke, or upon selected strokes as circumstances may require, producing a substantially straight running seam in which the base and superimposed layers are locked together by the loops of needle thread, preferably concatenated with a locking thread extending from one loop to the next and lying in a substantially straight line along or beneath the edge of the material. This 75 seam can be made rapidly by the mechanism disclosed herein and is especially adapted for many classes of work.

The nature of the invention will more fully appear from the following drawings, 80 the accompanying description, and will be pointed out in the annexed claims.

The drawings illustrate one of the preferred forms of mechanism embodying my invention.

Figure 1 is a vertical longitudinal sectional view of a sewing machine embodying my invention,

Fig. 2 is a front end view,

Fig. 3 is a vertical sectional view on lines 3—3, Fig. 1,

Fig. 4 is a detail plan view of the bender mechanism,

Fig. 5 is a detail sectional view of the bender adjusting mechanism, showing the 95 bender and its operating lever in elevation,

Fig. 6 is a detail view of the needle actuating mechanism,

Fig. 7 is a plan view of a preferred form of presser foot adapted for the stitching 100 mechanism disclosed, and

Fig. 8 is a perspective view of the seam made by the machine disclosed herein.

The sewing machine illustrated herein comprises the usual bed plate 1 from which 105 rises the standard 2 having an overhanging

5 arm 3 terminating in the usual head 4, a main driving shaft 5 having the usual driving pulley 6 and hand wheel 7 being mounted in suitable bearings 8, 9, 10, in said arm 5 and provided at its front end, which extends into the head with cams 11 and 12 adapted to operate respectively to oscillate the needle bar pitman 13 and the take-up 14.

10 In forming the seam above described the material is presented to the needle by a bender which presses together the base and superimposed layers in the path of the needle so that the needle will enter first the base layer and emerging therefrom will enter 15 the under surface of the superimposed layer. In order that the needle may be so positioned as to enter the base layer at a point well beyond the folded edge of the superimposed layer the needle is desirably maintained in a 20 fixed plane inclined to the work supporting surface of the work support and is so oscillated that the needle will normally enter beneath and beyond the edge of the superimposed layer and emerge therefrom at, or 25 beneath the edge of said layer, so that when the base layer is elevated by the bender the needle will first engage the base layer at the point where otherwise it would engage the superimposed layer, and passing through the 30 upper portion of the base layer will enter the superimposed layer, emerging therefrom at or beneath the edge thereof.

35 In the mechanism herein disclosed the needle bar which carries the oscillating needle is supported from a rigid bracket carried by the sewing machine head, said bracket preferably being made adjustable so that the position of entry and emergence of the needle from the material may be varied 40 within the requirements of this class of stitching.

45 In the mechanism disclosed herein the lower portion 15 of the head is thickened and is provided with a preferably vertical aperture in which is seated the stem 16 of a bracket 17 which is bifurcated at its lower end to provide journals 18, 19, adapted to receive the shaft 20 of the needle bar 21 which carries the curved needle 22.

50 The lower portion 15 of the head desirably may be provided with an extension 15^a adapted to support the complementary stitch forming mechanism which may as illustrated herein be in the form of a rotary hook 55 which may be driven from the main shaft by suitable gearing such as that illustrated herein.

50 The bracket 17 desirably is adjustably supported in the head 4 by a screw 23 seated in 60 the thickened portion 15 of the sewing machine head and which engages the cylindrical stem 16 of the bracket 17. The shaft 20, to one end of which the needle bar is rigidly secured, is provided at its opposite 65 end with an arm 24 to which is pivotally con-

nected a sleeve 25 which is screw threaded to receive the end of a link 26, the link 26 being also provided with a set nut 27 by means of which the effective length of the link 26 may be varied. The link 26 is provided 70 at its opposite end with a universal joint 28 by means of which it is connected to the lower arm 39 of a bell crank lever which is pivotally mounted upon a stud 30 projecting laterally from the sewing machine 75 head, the opposite end 31 of the bell crank being connected to the needle bar operating pitman 13.

It will be obvious from the mechanism above described that the reciprocation of the 80 pitman 13 by the cam 11 on the main shaft will cause the oscillation of the bell crank lever which will in turn reciprocate the link 26 and cause the oscillation of the needle bar and its needle. By reason of the universal 85 joint 28 connecting the needle bar with the arm 29 of the bell crank lever the positions of the plane of oscillation of the needle may be varied to cause the needle to enter a greater or less distance beneath the edge of 90 the superimposed layer so that the mechanism may be adjusted to cause the points of penetration and emergence of the needle in the material to lie in a line corresponding to the direction of the feed of the material or 95 may be positioned to cause the stitches to lie at a slight angle either to the right or to the left of the line of feed of the material.

The work support 32 is provided with a cylindrical stem slidably mounted in guides 100 in the bed plate 1 and yieldingly supported therein by a spring 33. The usual means may be provided for depressing the work support, which as shown in the drawing is in the form of a lever 34 engaging a lug 35 upon the work support and provided at its opposite end with a suitable knee lever (not shown) attached to a boss 36 on the end of the lever.

110 Any suitable mechanism may be employed to present the work to the stitch forming mechanism, the machine illustrated herein however, embodies a novel form of bender mechanism and also of feeding mechanism, the feeding mechanism being made the subject of a companion application filed concurrently herewith, Ser. No. 3,404. This feeding mechanism comprises a feed dog 32^x which is pivotally supported upon links 33^x, 34^x, which are yieldably mounted upon stems 115 extending into bosses in the frame of the machine. A rock shaft 35^x journaled in the work support is provided with an arm having an extension 36^x rotatably and slidably mounted in a guideway in the feed dog 32^x. The rock shaft 35^x is actuated by a link 37^x connected to a suitable rock shaft which, in the mechanism disclosed herein, is in the form of a sleeve surrounding a solid rock shaft. The oscillation of the hollow rock 120

shaft or sleeve imparts through the rock shaft 35^x a vertical movement to said feed dog. The solid rock shaft is connected by a link 38^x to the feed dog and gives said feed dog its forward and backward movement, as disclosed in the application aforesaid.

In order to present the base layer of material to the needle any suitable form of bender mechanism may be utilized, preferably however, the bender is made adjustable so that it may be thrust to a greater or less distance above the surface of the work support.

The bender 37 is mounted in suitable guides in the work support and is secured to a rod or stem 38 which is slidably mounted in lugs 39 extending laterally from an arm 40 secured to a rock shaft 41, the oscillation of which will cause the bender to be projected beyond the surface of a work support.

In order that the bender may yield when it engages an unusual obstruction such as a seam, means are desirably provided for permitting a yielding movement between the bender and its actuating mechanism. As disclosed herein the bender shaft 41 is provided at its opposite end with an arm 42 to which is pivotally connected a member 43 having laterally extending lugs 44, 45, said lugs being apertured in alignment to receive a stem 46 connected to a link 47 which is provided at its upper end with a yoke 48 embracing a cam 49 upon a countershaft 50 which is driven through a preferably worm gear 51 from a co-operating gear 52 upon the main driving shaft 5. The yoke 48 may be maintained in proper relation to the cam 49 by a link 53 pivotally connected at one end to a stud 54 on said cam and at its outer end to a shaft or stud 55 carried by the stand ard 2.

The lower end of the stem 46 is provided with a helical spring 56 the tension of which may be adjusted by set nuts 57 upon the end of the stem 46, said spring being seated at one end upon said nuts and at the other end upon the under surface of the lug 45. It will be obvious from the mechanism above described that any suitable ratio of gearing may be provided upon the main and countershaft to actuate the bender in synchronism with the oscillations of the needle; and that the bender may be actuated upon every stroke of the needle or upon every second or third or other stroke as it may be desired.

In the operation of the machine the rotation of the gear 52 of the main shaft will cause rotation of the gear 51 upon the countershaft which will reciprocate the link 47 through the yoke 48 and thereby cause oscillation of the arm 42 of the bender actuating shaft 41. By reason of the sliding connection between the stem 46 which extends downwardly from the link 47 and the member 43 which is supported therefrom by the spring 56 which encircles the stem 46 a yield-

ing connection is provided which will permit the full oscillation of the link 47 even though an obstruction to the bender prevents the normal oscillation of the bender actuating shaft 41.

In order to provide for an adjustment for the bender which will limit the upward movement thereof to adapt the bender for operation upon different thicknesses of material I have provided means located above the bed plate for adjusting the uppermost height of thrust of the bender. This desirably comprises a milled nut 60 seated in a recess 61 in the upper face of the bed plate and engaging a sleeve 62 which has upon its lower end a flange 63 engaging the under surface of the boss extending downward from the lower surface of the bed plate. The sleeve 62 is designed to receive a pin 64 engaging at its upper end the under surface of the milled nut 60 and at its lower end a lug or flange 67 upon the arm 40. The pin 64 is desirably provided with a shoulder or collar 68 which engages the lower end of a spring 68^x which is inclosed within the sleeve 62 and which bears at its upper end upon the under surface of the milled nut 60. It will be obvious that the pin 64 will be maintained in contact with the flange 67 on the arm 40 and that its upper end will reciprocate relatively to the under surface of the milled nut. By screwing the milled nut up and down the extent of reciprocation and consequently the extent of movement of the upper end of the material engaging end of the bender may be accurately adjusted. Furthermore, such adjustment can be conveniently effected by the operator from above the surface of the bed plate of the machine, which is highly advantageous.

In order to insure exactness and uniformity in the seam and particularly in respect to the points at which the needle shall emerge from the superimposed layer it is desirable that means be provided which will engage the superimposed layer adjacent to the edge thereof and maintain the edge of the superimposed layer at a fixed distance from the path of the needle. It will be obvious that various mechanisms, either movable or stationary, may be utilized for this purpose, but preferably the guide for the superimposed layer forms a part of the presser foot.

The preferred form of presser foot as illustrated herein comprises a horizontal member having laterally extending ears 69 secured to the depending extension 15^a of the head and with forwardly extending toes 125 70-71 having a recess 72 therebetween through which the superimposed layer is directed to the needle mechanism. The recess is preferably enlarged toward its rearward end to form a throat opening 73 oppo-

site to the position in which the bender rises through the work support.

The rearward portion of the toe 71 is provided with an angularly disposed flange 74 which curves upwardly from the toe 71 and finally merges into the body portion 68 of the presser foot. The flange 74 overlies the path of the needle and extends approximately to the vertical plane in which the bender reciprocates. By reason of this construction the upper surface of the superimposed layer can not be elevated beyond a predetermined point and the path of the needle being constant in its relation to the position of the flange 74 will necessarily emerge from the superimposed layer at the edge or at the same distance beneath the edge of said superimposed layer as may be predetermined by the adjustment of the needle mechanism. The forward end of the toe 70 may be provided with an edge guide 75 and also with a laterally extending flange 76 adapted to underlie the superimposed layer and separate the same from the base layer.

In the operation of the machine the base layer of material will pass beneath the presser foot while the superimposed layer will be guided beneath the curved flange 74 and finally pass beneath the presser foot beyond the rearward end of the flange. When the bender is thrust through the work support the base layer and the superimposed layer will be elevated against the overlying flange 74 and presented in the path of the needle so that the needle will first penetrate the upper surface of the base layer and emerging therefrom will penetrate the surface of the superimposed layer beneath and back from the edge thereof and will emerge from the superimposed layer at the edge thereof at a predetermined distance beneath said edge as may be desired.

If the bender is not pressed upwardly the separating guide 76 will raise the superimposed layer so that upon the succeeding oscillation of the needle it will pass over the base layer and enter the underside of the superimposed layer emerging at substantially the same point in or beneath the edge thereof as in the previous operation. This stitch however, is an idle stitch since it only lies in the superimposed layer. By suitable selection of the gears 51, 52 one or more of these idle stitches may be made intermediate of the stitches through the base and superimposed layer above described so that the superimposed layer may be caught to the base layer only at intervals but the edge will be stiffened and strengthened by the idle stitches taken therein.

In Fig. 8 I have illustrated a portion of a felled seam produced by the machine herein described, the superimposed layer being raised at one end to show the needle in the

position assumed by it when penetrating the base layer and emerging from beneath the edge of the superimposed layer.

It will be apparent from examination of this illustration that the needle penetrates first the upper surface of the base layer at a point *a* well back from the edge of the superimposed layer and emerging from the base layer immediately enters the superadjacent surface of the superimposed layer at *b*, emerging from said superimposed layer at a point *c* at or preferably, (as illustrated herein,) beneath the edge of the superimposed layer. When the concatenating thread *y* has been passed through the loop of needle thread and the stitch set by the take-up mechanism the interlaced loops will be drawn within the superimposed layer as shown.

It will be understood that if the bender is raised to present the base layer to the needle at every stitch the seam will comprise a series of stitches of the character above described.

If, however, the bender is actuated intermittently, one or more idle stitches may be made in the superimposed layer between the successive stitches which penetrate both layers. Where as in the machine illustrated herein the ratio of movement of the bender to that of the stitch forming mechanism is one to two, the next penetration of the needle after the formation of the stitch above described will be at the point *d* in the superimposed layer, the point of emergence of the needle being at the point *e* beneath the edge of the superimposed layer, corresponding in position in respect to the edge of said layer to the point of emergence *c* of the needle in the preceding stitch. When the concatenating thread is passed through the loop and the stitch set the interlaced loops will be drawn within the superimposed layer like those of the preceding stitch so that the resulting seam, when viewed by turning back the edge of the superimposed layer, will present a substantially straight line of stitches.

While a rotary hook is disclosed herein as the means for introducing a concatenating bobbin thread into the loops of needle thread it is to be understood that the embodiment of the invention is illustrative merely; that any other well known complementary stitch forming mechanism, such as a shuttle looper, etc., may be used to concatenate the loops of needle thread; furthermore that a chain stitch may be formed in place of the lock stitch shown by slight changes in the mechanism which will be obvious to those skilled in the art of sewing machines.

Any suitable feeding mechanism may be utilized in connection with this invention, such as that illustrated herein, but inasmuch

as the particular feeding mechanism forms no part of this invention, detailed description thereof will be unnecessary.

Having thus described my invention what 5 I claim as new and desire to secure by Letters Patent is:

1. A blind stitch sewing machine comprising a work support, a curved oscillating needle and complementary stitch forming mechanism located above the work support; means for maintaining and operating the needle above the work support in a fixed plane inclined with relation to the work supporting surface of the work support, and 10 means for presenting the material in the path of the needle.

2. A blind stitch sewing machine for felling a superimposed layer upon a base layer of material comprising a work support, a curved oscillating needle and complementary stitch forming mechanism located above the work support; means for maintaining and operating the needle in a fixed plane inclined with relation to the work supporting surface of the work support and means for presenting the material in the path of the needle whereby the needle will enter the base layer beneath and beyond the edge of 25 the superimposed layer and will emerge from the superimposed layer at or beneath the edge thereof.

3. A blind stitch sewing machine for felling a superimposed layer upon a base layer of material comprising a work support, a curved oscillating needle and complementary stitch forming mechanism located above the work support and means for feeding the work across the work support; means for 30 maintaining and operating the needle in a fixed plane inclined with relation to the work supporting surface of the work support and substantially parallel to the line of feed and means for presenting portions of 40 the material in the path of the needle whereby the needle will enter the base layer beneath and beyond the edge of the superimposed layer and will emerge from the superimposed layer at or beneath the edge thereof.

4. A blind stitch sewing machine for felling a superimposed layer upon a base layer of material comprising a work support, a curved oscillating needle and complementary stitch forming mechanism located above the work support and means for feeding the work across the work support; means for maintaining and operating the needle in a fixed plane inclined with relation to the work supporting surface of the work support and substantially parallel to the line of feed; a bender, and means for actuating the same at intervals to present the base layer in the path of the needle whereby the needle will form a stitch in the base and 55 superimposed layer entering the base layer

at a point beneath and beyond the edge of the superimposed layer and emerging from the superimposed layer at or beneath the edge thereof.

5. A blind stitch sewing machine for felling a superimposed layer upon a base layer of material comprising a work support, a curved oscillating needle and complementary stitch forming mechanism located above the work support and means for feeding the work across the work support; means for maintaining and operating the needle in a fixed plane inclined with relation to the work supporting surface of the work support and substantially parallel to the line of feed; a bender and means for actuating the same only upon certain thrusts of the needle to present the base layer in the path of the needle whereby the needle will enter said base layer beneath and beyond the edge of the superimposed layer and emerge from the superimposed layer at or beneath the edge thereof and will upon intermediate thrusts enter and emerge from the superimposed layer alone.

6. A blind stitch sewing machine for felling a superimposed layer upon a base layer of material comprising a work support, a curved oscillating needle and complementary stitch forming mechanism located above the work support and means for feeding the work across the work support; means for maintaining and operating the needle in a plane of fixed inclination relative to the work supporting surface of the work support, means for adjusting the position of the plane of oscillation of the needle with respect to the line of feed and means for presenting portions of the material in the path of the needle.

7. A blind stitch sewing machine for felling a superimposed layer upon a base layer of material comprising a work support, a curved oscillating needle and complementary stitch forming mechanism located above the work support and means for feeding the work across the work support; means for maintaining and operating the needle in a fixed plane inclined with relation to the work supporting surface of the work support, a bender and means for actuating the same to present the base layer in the path of the needle, means engaging the upper surface of the superimposed layer adjacent to the edge thereof and adapted to maintain a fixed relation between the upper surface of the superimposed layer and the path of the needle whereby the points of emergence of the needle from the superimposed layer will lie at a fixed distance from the upper surface and from the edge of said layer.

8. A blind stitch sewing machine for felling a superimposed layer upon a base layer of material comprising a work support, a curved oscillating needle and complementary

stitch forming mechanism located above the work support and means for feeding the work across the work support; means for maintaining and operating the needle in a fixed plane inclined with relation to the work supporting surface of the work support, a bender and means for actuating the same to present the base layer in the path of the needle, a presser foot having an inclined flange overlying the path of the needle and engaging the upper surface of the superimposed layer, thereby maintaining a fixed relation between the upper surface of the superimposed layer and the path of the needle, whereby the points of emergence of the needle from the superimposed layer will lie at a fixed distance from the upper surface and from the edge of said layer.

9. A blind stitch sewing machine for fell-ing a superimposed layer upon a base layer of material comprising a work support, a curved oscillating needle and complementary stitch forming mechanism located above the work support and means for feeding the work across the work support; means for maintaining and operating the needle in a

fixed plane inclined with relation to the work supporting surface of the work support, a bender and means for actuating the same upon predetermined cycles of the stitch forming mechanism to present the base layer in the path of the needle whereby the base layer and superimposed layer will be united and in other cycles the needle will engage only the superimposed layer to form idle stitches, a presser foot having an inclined flange overlying the path of the needle and engaging the upper surface of the superimposed layer to maintain a fixed relation between the same and the path of the needle whereby the points of emergence of the needle from the superimposed layer will lie at a fixed distance from the upper surface and from the edge of said superimposed layer in both the fixed and idle stitches. 45

In testimony whereof I have signed my name to this specification in the presence of two subscribing witnesses.

THOMAS J. HAYES.
